UNITED STATES PATENT OFFICE.

OCTAVE BUREAU, OF WATERVILLE, MAINE.

CARPENTER'S WORKHOLDER.

Application filed October 31, 1923. Serial No. 671,967.

To all whom it may concern:

Be it known that I, OCTAVE BUREAU, a citizen of the United States, residing at Waterville, in the county of Kennebec and 5 State of Maine, have invented certain new and useful Improvements in a Carpenter's Workholder, of which the following is a specification.

This invention relates to improvements in 10 carpenters' work holders.

The primary object of this invention is the provision of a work holder especially adapted for use by carpenters which embodies a cooperative arrangement of vise and adjustable clamps and stops.

A further object of this invention is the provision of a carpenter's work holder which embodies a compact arrangement of work handling devices conveniently assembled in 20 a cooperative relation, and in this respect differing from the present work handling devices of carpenters which are scattered about the carpenter's bench, taking up much room and rendering it difficult to perform 25 some operations in a facile and expeditious manner.

A further object of this invention is the provision of a novel type of adjustable bench stop.

30 Other objects and advantages of this invention will be apparent during the course of the following detailed description.

In the accompanying drawings, forming a part of this specification, and wherein 35 similar reference characters designate corresponding parts throughout the several views.

Figure 1 is a plan view of the improved carpenter's tool, showing the manner of connection to a bench.

Fig. 2 is a side elevation of the carpenter's tool, showing important details of construction thereof.

Fig. 3 is a cross sectional view taken substantially on the line 3—3 of Figure 2.

Fig. 4 is a cross sectional view taken substantially on the line 4—4 of Figure 1.

Fig. 5 is a transverse cross sectional view taken substantially on the line 5—5 of Figure 2.

In the drawings, wherein for the purpose of illustration is shown but the preferred embodiment of this invention, the letter A may generally designate the improved device which is adapted to be positioned upon a bench B, such as an ordinary

carpenter's bench, and which may include a vise construction C, and novel adjustable bench stop or abutment construction D.

The vise structure C is of novel construction, embodying a supporting box or casing 60 10 of elongated formation, which provides a compartment 11 therein. It includes the side walls 12 and 13; a top wall 14; and one end wall 16 preferably having an opening 17 therethrough. The front of the housing 10 is preferably provided with a stationary jaw 20 flanged thereon at right angles to the run of the box 10; the compartment 11 preferably being entirely open at the front 70 of the box 10 adjacent the stationary jaw 20.

A slidable jaw structure 21 is provided for cooperation with the above described structure of the vise C, which includes a substantially U-shaped elongated casing 23 75 adapted for sliding engagement in the compartment 11 of the vise casing or box 10; and the jaw 25 which may be appropriately termed the sliding jaw of the vise C. The U-shaped sliding portion 23 of the sliding 80 jaw structure 21 preferably is polygonal in its U-shaped cross section, providing the side walls 27; a top wall 28; and a rear wall 29 having an opening 30 therein in aligning relation with the opening 17 above mentioned. The supporting casing 10 of the vise is preferably provided with a transverse supporting bar 33 integral therewith intermediate its ends, and at the bottom thereof, upon which the sliding portion 23 of the 90 jaw structure 21 rests. Also, a transverse bottom bar 35 is provided integral with the casing structure 10, adjacent the stationary jaw 20, upon which the lower edges of the side walls 27 slide to also support the sliding 95 jaw in a determined relation with respect to the stationary jaw structure of the vise C.

A screw 40 is rotatably supported by the sliding jaw structure 21, having a bearing in 100 a suitable opening 41 provided in the sliding jaw 25; outwardly of the sliding jaw 25 having a suitable handle 42 therein of the well known type. The screw threaded portion of the screw member 40 extends longitudinally through the compartment of the U-shaped portion 23 of the jaw structure 21, and is adjustably engaged within the threaded opening 43 of the projecting end 44 of a detachable arm 45 which is connected, as 110 by screws 46, to the transverse bar 33 above mentioned.

In connection with the attachment of the vise structure C to the work bench B, a supporting arm 50 is preferably provided adjacent the rigid jaw 20 and integral therewith, offset as by a flange 51 from the plane of the stationary jaw 20, so that the supporting arm 50 may overlie the rear of a side wall 52 of the bench B, and be bolted thereto as by bolts 53, or the like. It is to be noted that the marginal edge of the bench wall 52 then rests against the offset flange 51, so that the work engaging surface of the stationary jaw 20 lies flush with the outside surface of the bench wall 52, substantially as is illustrated in Figures 1 and 3 of the drawings. A second supporting arm 54 is preferably provided in connection with the vise E, which provides a socket 55 at its outer end adapted to receive the rear portion of the vise box or casing 10 therein. At its other end the supporting arm 54 may be bolted, as at 56, beneath the table or top 57 of the bench B. A suitable opening 59 may be provided in the socket portion of the supporting arm 54, adapted to align with the opening 17 of the vise casing 10, and thru which the adjustment screw 40 may pass during adjustment of the jaws of the vise into a certain relation.

The sliding jaw 25 is of somewhat novel formation, providing a portion 25^a with a working surface which is disposed in a parallel plane at all times with respect to the plane of the stationary jaw 20. However, at the lateral portion of the slide jaw 25, a portion 25^b thereof is outturned at an obtuse angle with respect to the portion 25^a, so that the plane defined by the portion 25^b is in acute angular relation with respect to the plane of the stationary jaw 20, and provides a wedge crevis with respect to the stationary jaw 20, adapted to receive pieces of work in working relation therein, similar to the bench stops now used by carpenters.

Referring to the adjustable bench stop or abutment device D, the same preferably includes a frame 60, which consists of upper and lower horizontal bars 61 and 62 respectively, connected at their ends by means of vertical cylindrical shaped posts 64 and 65. The posts 64 and 65 are each slidably disposed through laterally extending guide lugs 66 which are integrally carried as a part of the vise housing 10, extending laterally of the side wall 13 thereof. The frame 60 is vertically adjustable, and to this end rotatably carries an adjusting screw 70, which is rotatably supported in a suitable bearing between the ends of the lower bar 62. Below the bar 62 the screw 70 provides a crank 71. The threaded portion of the screw 70 threadably engages through a laterally extending lug 73 which may be integrally formed with respect to the vise housing or casing 10.

The bar 61 of the frame 60, at the end thereof adjacent the stationary jaw 20 of the vise C is preferably provided with a fixed jaw 75 disposed in a vertical plane; said jaw 75 being in such a relation to the work bench B, that the same does not interfere with the table portion 57 thereof, and is disposed rearwardly of the attaching ends of the supporting arms of the tool A, and in the space between said supporting arms. An adjustable jaw 76 is slidably carried by the upper horizontal bar 61, providing a face portion 77 which is disposed in a plane at an acute angle with respect to the work engaging face of the fixed jaw 75. The jaw structure 76 provides a socket portion 78 which has an opening 78^a therein which slidably receives the bar 61, and this socket portion 78 preferably has an opening (not shown) therein which may align with any of a series of openings 79 disposed longitudinally in the bar 61, so that a cotter pin 80 may be inserted therethrough to lock the jaw structure 76 in a fixed relation to the bar 61 and to the jaw 75.

The fixed jaw structure 75 preferably provides a fixed shelf 82 thereon, adjacent the marginal edge of the table 57 of the work bench B, to which may be suitably clamped, a notched plate or toothed bench hook or stop 85, as by screws 86.

Referring to the operation of the improved work holding device A, the jaws 20 and 25 thereof may of course be used in much the same manner as the ordinary vise, although the jaw 25 presents a novel feature in the provision of the angled portion 25^b, which can cooperate at an acute angle with respect to the fixed jaw 20 in providing an adjustable stop for work engaging purposes. By means of vertical adjustment of the frame 60 it can readily be understood that the jaws 75 and 77 may be elevated to the desired degree, and the jaw 77 slid along the bar 61 with respect to the jaw 75 to the proper degree to receive a piece of work of a predetermined size for planing or the like thereof. The provision of the notched plate 85 is a novel feature of this invention, as it is not located in the top of the work bench B, but is adjustable with respect to the plane of the table 57 thereof for work engaging purposes, as will be readily understood by those skilled in the art to which this invention relates.

From the foregoing description of this invention it will be apparent that the improved device A provides a compact and simple arrangement of details which will permit of the provision of a combined vise and adjustable stop structure of a universal character, which may be attached to a carpenter's bench or the like in an out of the way position.

Various changes in the shape, size, and arrangement of parts may be made to the

form of the invention herein shown and described, without departing from the spirit of this invention or the scope of the claims.

I claim:

- 5 1. In an adjustable bench stop the combination of a supporting body providing guide lugs thereon, a polygonal shaped frame including upper and lower bars and end posts connecting said bars, said end posts adapted for sliding engagement through said guide lugs, means connected to the lower bar and engaging said supporting body to permit selective adjustment of the frame with respect to said supporting body, and adjustable jaw means carried by the upper bar of said frame.
- 10 2. In a device of the class described, the combination of a supporting body, supporting arms carried by said supporting body, a frame adjustably supported by said supporting body, inwardly of the attaching ends of said supporting arms, fixed and movable jaws carried by said frame, and a toothed stop carried by said fixed jaw.
- 15 3. In combination with a bench, a supporting body, supporting arms for connecting said supporting body in spaced relation to said bench, a frame vertically adjustable upon said body, fixed and movable jaws supported by said frame in spaced relation with said bench to which the supporting arms are attached, and a toothed stop carried by the fixed jaw of said vertically adjustable frame with the teeth thereof in facing relation toward the bench and in spaced relation therewith.

- 20 4. In a device of the class described the combination of an elongated supporting body, arms fixedly connected to said supporting body whereby said body may be connected to a suitable work bench in spaced relation therewith, a frame vertically adjustable on said supporting body and between the supporting arms thereof, fixed and movable jaws having their work engaging faces disposed in acute angular relation supported by said vertically adjustable frame, and a toothed stop carried by one of the jaws of said vertically movable frame.

5. In a device of the class described the combination with a work bench including a top having a marginal edge, an elongated supporting body, arms connected to the work bench for supporting the elongated supporting body in spaced relation with the work bench laterally thereof and substantially parallel with the facing marginal edge of the work bench, a frame adjustably carried by said supporting body in the space between the supporting body and the facing marginal edge of the work bench, and stationary and movable jaws carried by said adjustable frame providing an adjustable bench stop the jaws of which may be relatively moved on the frame toward and away from each other and may be moved toward and away from the plane of the bench top by said adjustable frame.

6. In an adjustable bench stop the combination of a supporting body, a substantially polygonal frame including upper and lower bars and end supporting posts, said supporting body having laterally extending lugs for slidably receiving the end supporting posts whereby the frame may be vertically moved, an adjustable screw member rotatably carried by the lower bar of the frame in screw threaded adjustable engagement with said supporting body whereby upon rotation of the same the frame may be fed vertically with respect to the supporting body, a fixed jaw carried by said upper bar of the frame, and a movable jaw slideable on the upper bar of the frame with respect to the fixed jaw.

7. In a device of the class described the combination of a supporting body, a frame including upper and lower bars and end posts supporting said bars, means carried by the supporting body slidably receiving the end posts of said frame for vertical sliding movement with respect to said frame, a jaw fixed upon said upper bar, a jaw adjustable along the upper bar with respect to the first mentioned jaw, and adjusting means carried by the lower bar and by the supporting body whereby to vertically adjust said frame with respect to the supporting body.

OCTAVE BUREAU.
